UNITED STATES PATENT OFFICE.

WILLIAM GIFFORD JONES, OF EVANSTON, ILLINOIS, ASSIGNOR TO ACCOUNTING DEVICES COMPANY, OF EVANSTON, ILLINOIS, A CORPORATION OF ILLINOIS.

FLEXIBLE POST OR CHAIN.

1,184,349.

Specification of Letters Patent. Patented May 23, 1916.

Application filed November 10, 1915. Serial No. 60,734.

To all whom it may concern:

Be it known that I, WILLIAM GIFFORD JONES, a citizen of the United States, residing at Evanston, in the county of Cook and 5 State of Illinois, have invented a new and useful Improvement in Flexible Posts or Chains, of which the following is a specification.

The present invention relates particularly 10 to a flexible post or chain, for use in loose-leaf binders, or in analogous situations.

The primary object is to provide a chain 15 of simple and cheap construction, which may be advantageously employed in loose-leaf binders, such as, for instance, the loose-leaf ledger described and claimed in United States Patent No. 1,155,067, granted September 28, 1915, on my application.

The invention is illustrated in its preferred embodiment in the accompanying drawing, in which—

Figure 1 represents a broken sectional view 20 of a binder-frame equipped with my improved flexible post; Fig. 2, a sectional view taken as indicated at line 2 of Fig. 1; Fig. 3, a fragmentary view of the improved chain; Fig. 4, a plan view of the same; Fig. 5, a plan view of one of the main links employed, and Fig. 6, an end view of the same.

In the construction illustrated, A, A' represent the binding or clamping members of 30 a loose-leaf binder; and B represents my improved chain-post, or flexible post, applied thereto.

In a binder of the construction described 35 in the above mentioned patent, clamping members of the binder have mounted therein right and left threaded screw-rods which are equipped with nuts, to which the extremities of the chain-post are attached. By this means, the chains may be taken up and placed under the desired tension after the leaves have been inserted in the binder.

In the accompanying drawing, each 45 clamping member is shown provided with a screw-rod 1 equipped with a nut 2, to which the ends of the chain-post B are secured. The end-portions of the chain-post extend about bearings 3 into the clamping members of the binder, as shown. The chain comprises a series of main slotted rod-form links 4, and a series of flat links 5 connecting the links 4.

Each link 4 preferably comprises a short 55 rod-section having a longitudinal groove 4^a

milled in one side thereof; and the flanges formed by the milling operation are provided with two transverse sets of perforations 4^b, which receive the pivots 6. The ends 4^c of each link 4 are inclined in the 60 same direction with respect to the axis of the link. The shoulders 4^c of the links abut against each other when the chain is straight, so that the chain can flex in one direction only about the pivots 6. The inclined shoulders 4^c are adapted to give continuity of surface to the chain-post, so that the perforated leaves may slide freely on the post without danger of catching in the joints.

Each link 5 is flat and of suitable thickness to fit snugly within the groove 4^a, without, however, interfering with the freedom of the flexing of the chain in the one direction in which it is intended to be flexed. 75 Each link 5 has its ends rounded, as indicated at 5^a; and each link 5 preferably has its outer lateral edge provided with a slight curved recess 5^b. Thus, each link 5 has at one lateral edge the slightly raised curved 80 projections 5^c flanking the recess 5^b. The curved portions 5^c preferably project very slightly above the edges of the flanges formed by the slot 4^a. The purpose is to facilitate the sliding of the chain over the 85 curved bearings 3.

It will be noted that the construction is such that the chain-post can be flexed in one direction only; and as a pair of chains is ordinarily employed in each binder in such 90 manner that the chains are in reversed relation, the effect is to maintain the loose-leaves securely in a non-shiftable position in the binder. Preferably, the end links of the chain-post are similar to the links 4, but provided at one end with a projection or stem 95 4^d, by means of which the extremity of the chain is securely attached to the nut 2. In the illustration given, the stem 4^d is threaded and equipped with a nut 4^e.

It will be understood from Fig. 2 that the improved chain-post is of substantially circular cross-section; and it will be further understood from the description given that the loose-leaves can be slid upon the chain-post without danger of catching in the joints. It may be added that the links 4 may be cheaply formed, either by a drop-forging process, or by milling a rod of suitable length longitudinally and then cutting 110

the rod in oblique planes to form the links with the inclined end-shoulders. Also, the links 5 may be formed by a drop-forging process, or by stamping them from heavy sheet-metal, as desired.

The foregoing detailed description has been given for clearness of understanding, and no unnecessary limitation should be understood therefrom; but the claims should be construed as broadly as permissible, in view of the prior art.

What I regard as new, and desire to secure by Letters Patent, is—

- 15 1. A chain-post of the character set forth, comprising a series of grooved rod-form links having abutting end-shoulders, a series of flat links housed in the grooves of said first-named links, and pivots connecting said links.
- 20 2. A chain-post of the character set forth, comprising a series of rod-form links having abutting inclined ends and provided at one

side with a longitudinal groove, a series of flat links housed in said groove, and pivotal connections between said links.

25

3: A chain-post of the character set forth, comprising a series of links having abutting end-shoulders formed to afford an overlap and give continuity of surface, said links having grooves at one side, a series of flat 30 links housed in said grooves, and pivots connecting said links.

4. A chain-post of the character set forth, comprising a series of rod-form links having inclined abutting ends and provided at 35 one side with longitudinal grooves, a series of flat links housed in said grooves and having curved edge-portions projecting beyond the edges of the flanges of said first-named links, and pivots connecting said links.

WILLIAM GIFFORD JONES.
